Primary Examiner — Mark T. Philipp(74) *Attorney, Agent, or Firm* — Ziegler IP Law Group, LLC.(57) **CLAIM**

The ornamental design for a pump for inflating tyres as shown and described.

DESCRIPTION

FIG. 1 is a front, right and top side perspective view of a pump for inflating tyres showing our new design;

FIG. 2 is a rear, left and bottom side perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is an enlarged view of the portion marked '9' of FIG. 7.

The broken lines shown in the drawings represent portions of the pump for inflating tyres that form no part of the claimed design.

1 Claim, 9 Drawing Sheets(56)
